GRANULAR AMMONIUM NITRATE
EXPLOSIVE

Charles D. Bitting, Kenvil, N. J., assignor to
Hercules Powder Company, Wilmington, Del.,
a corporation of Delaware

No Drawing. Application April 12, 1941,
Serial No. 388,262

7 Claims. (Cl. 52--11)

This invention relates to a new blasting explosive composition and to a method for the manufacture thereof and in particular to a blasting explosive of the permissible type which is especially adapted for use in producing lump coal.

It is well known in the art that the sustained heaving action of black powder is the most desirable type of force available if it is desired to produce lump coal. This sustained heaving action is due to the low rate of detonation of black powder, which rate classes black powder as a deflagrating explosive and not as a detonating explosive. However, black powder cannot be used in gaseous mines due to the flame characteristics, since the flames produced quite often cause explosions of fire damp and the like.

The art has produced the permissible explosives to overcome the difficulties encountered in the flame characteristics which are inherent in black powder, and these permissible explosives, while approaching black powder in efficiency and being safer than black powder to use, have not duplicated the sustained heaving action which is characteristic of black powder as used in the production of coal.

It is the object of this invention to produce an improved explosive composition especially adapted for the production of coal.

It is a further object of this invention to provide a method for the manufacture of an improved explosive composition suitable for use in mining coal.

It is a further object of this invention to produce a permissible explosive which will have a sustained heaving action upon detonation.

It is a further object of this invention to provide a method of manufacturing a permissible explosive which has a sustained heaving action similar to that associated with black powder.

It is a further object of this invention to provide a method of producing pellets comprising ammonium nitrate.

It is a still further object of this invention to provide a means of impregnating and pelletizing a mixture which when used with nitroglycerin will provide a permissible explosive having a sustained heaving action upon detonation.

Other and further objects of this invention will be apparent hereinafter.

The objects of this invention have been accomplished by graining or pelleting admixtures comprising ammonium nitrate and a binding or adhesive agent into granules having a predetermined size and then admixing with these granules sufficient liquid explosive nitric ester to give the

desired sensitivity and explosive properties. In particular an explosive composition in accordance with this invention has been prepared by admixing ammonium nitrate, a carbonaceous material, and starch in the presence of a wetting agent, preferably water, which may be supplied by adding to the mixture liquid water or by using salts containing water of crystallization. The admixing of the materials is easily accomplished by raising the temperature of the salt to effect melting or fusing, adding carbonaceous and adhesive agents thereto, and while the admixture is in a molten condition or close to a molten condition, passing this molten or semi-plastic admixture through a screen, cooling the screened material and admixing with the screened material the desired amount of liquid explosive nitric ester.

In particular, it has been found that highly desirable granules may be obtained by passing the molten or semi-plastic materials made by admixing ammonium nitrate, carbonaceous material, a hydrated salt, and a binder, such as for example, starch through an 8-mesh screen and allowing the screened material to fall through a column of cool air, recovering the granules which have thus been cooled and hardened, and then admixing therewith between about 5% and about 15% nitroglycerin or an equivalent liquid explosive nitric ester, such as nitroglycol, nitro sugars, nitrated diethylene glycol, and the like.

A low rate of detonation of the explosive has been found possible by controlling the particle size of the granules used by passing the material through the desirable smaller or larger mesh screens. Also by varying the amount of nitroglycerin added to the granules, the detonation rate may be altered.

By controlling the screen size of the granules and/or by varying the type of carbonaceous material used, an explosive having a wide range of cartridges per unit weight is easily developed. Thus, it is perfectly possible to manufacture explosives which have the cartridge count of from about 300 to 500 $1\frac{1}{4}$ x 8" cartridges per hundred pounds of explosive. The explosives so produced will have a relatively high sensitivity by the half cartridge sensitivity test and will exhibit velocities which may vary from about 1,200 to 2,000 meters per second depending upon the coordination of granule particle size and percentage of nitroglycerin.

In preparing the granules to which is added the liquid explosive nitric ester, it is preferable to admix with a preponderance of ammonium ni-

trate an amount of salt containing water of crystallization, such as for example, magnesium nitrate containing six molecules of water, calcium nitrate containing four molecules of water, or sodium sulfate containing seven molecules of water, heating this admixture of salt and then adding thereto sufficient starch or other adhesive material, insoluble in liquid explosive nitric esters, cooling the admixture to a semi-plastic condition and converting the semi-plastic material into granules of the desired size. The granules may be produced by cooling of the material in a grainer, such as a revolving drum or a heated evaporating pan having a plow therein or by passing the semi-plastic mass through a screen of the desired size.

It is oftentimes desirable to add various other ingredients to the mix of ammonium nitrate, wetting agent, and binder and such additive ingredients may be for example, sodium nitrate to increase the oxygen content of the explosive or a carbonaceous material, such as balsa, bagasse, ivory meal, wood flour, manioc, and the like to control the oxygen balance of the admixture and also to control the density of the material when it is grained into its final granule form.

Although I have found it preferable to use various salts containing water of crystallization in order to wet the adhesive and aid in the forming of a molten or plastic mass, I may also use water per se in order to obtain the desired end. Thus, water may be added to the admixture at any time during the mixing of the various ingredients, or if desired, the water may be added with the starch or adhesive by forming an aqueous solution of adhesive material and adding said solution to the admixture.

The granules which are produced by admixing the materials described hereinbefore when cooled to room temperatures have a hard outer surface which is comparatively non-absorbent and when the liquid explosive nitric ester is added to these granules the liquid explosive is substantially maintained on the surface of the non-absorbent grains and provides the finished explosive with the desired sensitivity. It has been found that the preferable amount of liquid explosive nitric ester, usually nitroglycerin, lies between about 5 and 8% as this liquid explosive content provides the explosive with the low detonation rate desirable for producing the heaving action. The explosive possesses detonation characteristics similar to those possessed by black powder.

In order to further illustrate the new explosive of this invention and to point out in particular the method of producing the explosive, the following examples are given. All parts and percentages used are by weight.

EXAMPLE 1

A pelleted product was prepared by impregnating ivory meal with a salt mixture comprising ammonium nitrate 77%, magnesium nitrate 7.3%, sodium nitrate 10.4%, sodium chloride 5.0% and starch. This material after admixing had the following composition.

Composition	Percentage
NH_4NO_3	30.3
$\text{Mg}(\text{NO}_3)_2 \cdot 6\text{H}_2\text{O}$	2.9
NaNO_3	4.1
NaCl	1.9
Starch	5.9
Fine ivory meal	54.9

The pelleted ivory meal having the above composition was prepared in a grainer by adding starch and the ivory meal to the salts which were melted together at a temperature of 250° F. The admixture was stirred for about 30 minutes and then cooled to below 100° F., removed from the grainer and screened. About half of the charge was pelleted so that it would not pass an 8-mesh screen and the other half was pelleted so that all passed an 8-mesh screen and about 20% passed a 40-mesh screen. The pellets produced were extremely hard and tough and adaptable for use in explosive formulations.

In order to determine the usefulness of the pelleted material in an explosive formulation, the following composition was prepared:

To an admixture of 74.3% ammonium nitrate, 3% sodium nitrate, 0.5% chalk, and 16.2% of the pelleted material described hereinbefore but screened between 8 and 40-mesh screens was added 6% nitroglycerin. The formulation after thorough mixing was packed in 1 1/4 x 8" cartridges and gave a count of 302 cartridges per 100 pounds of explosive. The Cordeau rate was 1,500 m./sec. and the sensitivity was 16 inches. After five days' storage at 110° F., the Cordeau rate was 1,200 m./sec. and the sensitivity was 12 inches by the standard half cartridge sensitivity test.

EXAMPLES 2-7

Various other carbonaceous materials have been treated with salt melt, and starch and then pelleted through a screen to provide examples of explosives. The pelleted materials were admixed with a liquid explosive nitric ester usually and preferably nitroglycerin to form an explosive composition. The table below shows the composition of six samples of material pelleted with the aid of starch.

Table I

		Pellet No.					
		2	3	4	5	6	7
45	Salt melt	78.0	75.0	40.0	33.4	35.4	66.7
46	Bagasse-Celotex	19.0	12.0				
47	Starch	3.0	2.0	2.0	1.3	1.2	6.7
48	Fine ivory meal		11.0	58.0	32.0	22.5	
49	Fine oat hulls						19.3
50	Wood pulp						7.3
51	NH_4NO_3				33.3	40.9	
52	Screen temp. °F.	200	200	225	225	180-190	210-220

	Composition before melting
* Salt melt ingredients:	
NH_4NO_3	77.3
$\text{Mg}(\text{NO}_3)_2 \cdot 6\text{H}_2\text{O}$	7.3
NaNO_3	10.4
NaCl	5.0

55 In preparing the pelleted material, the carbonaceous ingredients were added to the salt which was in a melted condition and held at 250° F., the admixture thoroughly stirred for about 15 minutes, allowed to cool and screened through an 8-mesh screen which was held four to five feet above the floor. The pelleted material passing through the screen dropped through the four or five feet of air and was cooled to an extent that produced pellets which maintained their granular form, were hard and non-absorbent.

60 The above six samples of pelleted material were used in dynamite formulations in accordance with the following table:

Table II

	Powder composition, percent					
	2	3	4	5	6	7
Nitroglycerin	6.0	6.0	5.0	5.0	5.0	5.0
NH ₄ NO ₃	51.0	55.7	73.5	60.2	50.4	63.8
NaNO ₃

Pellet #3 Table I		37.8				
Pellet #4 Table I			17.0			
Pellet #5 Table I				31.3		
Pellet #6 Table I					42.1	
Pellet #7 Table I						28.7
Chalk	0.5	0.5	0.5	0.5	0.5	0.5
Tests:						
Count (1 1/4 x 8")/100 lbs.	398	352	290	310	336	314
Rate by Cordeau—normal (m.s.)	1,460	1,410	1,390	1,290	1,280	1,280
Sens. normal, inches	8	12	12	20	20	20

EXAMPLE 8

To produce a desired ingredient 27.2 parts of potato starch dissolved in 500 parts of water were admixed with 152 parts of 50/50 balsa/bagasse and after partially drying this admixture, a molten mass comprising

	Parts
NH ₄ NO ₃	436.8
Mg(NO ₃) ₂ ·6H ₂ O	45.6
NH ₄ Cl	28.8
NaNO ₃	109.6

was added thereto with stirring. The stirring was continued until the carbonaceous material had absorbed the salt or become impregnated therewith and a granular product formed. This granular product was used in a dynamite formulation which had the following properties.

Granular product	per cent	73
Nitroglycerin	do	12
NH ₄ NO ₃	do	8
NaNO ₃	do	7
1 1/4" x 8" ctgs./100 lbs.		521
Cordeau rate m.s.		1,639
Sensitiveness—normal	inches	18

EXAMPLE 9

A granular product was produced in accordance with Example 8 except that the starch solution was added after the balsa/bagasse had been treated with the molten salt admixture. The material after addition of the starch was heated and stirred until dry. The granular product was used in a dynamite formulation which had the following properties.

Granular product	per cent	73
Nitroglycerin	do	12
NH ₄ NO ₃	do	8
NaNO ₃	do	7
1 1/4" x 8" ctgs./100 lbs.		444
Cordeau rate m.s.		1,785
Sensitiveness—normal	inches	24

EXAMPLE 10

A granular product was produced in accordance with the procedure of Example 9 except the starch added to the balsa/bagasse was in the dry state. The material was stirred until the starch had been thoroughly dissolved and distributed through the mass. The granular product after cooling was used in a dynamite formulation which had the following properties.

Granular product	per cent	73
Nitroglycerin	do	12
NH ₄ NO ₃	do	8
NaNO ₃	do	7
1 1/4" x 8" ctgs./100 lbs.		574
Cordeau rate m.s.		1,620

Sensitiveness—normal inches 10

From the above examples, it will be seen that the pelleted salt-carbonaceous-adhesive admixture when admixed with a liquid explosive provides an explosive composition having a low rate of detonation and a high sensitivity. This type explosive gives unusual advantages when lump material is to be produced. The explosive gives a heaving action similar to black powder which is highly desirable since this type action prevents the production of large amounts of fines.

It will be understood that the details and examples hereinbefore set forth are illustrative only and that the invention as broadly described and claimed is in no way limited thereby.

What I claim and desire to protect by Letters Patent is:

1. The method of preparing a granulated explosive, which method comprises intimately intermingling a preponderant amount of ammonium nitrate, starch, a carbonaceous combustible ingredient, and water in an amount less than 5% of the entire composition, subjecting the mixture to the action of heat, forming the blend of materials, while still plastic, into distinct agglomerates of controlled size, cooling to convert said agglomerates into firm, free-flowing grains, and surface-coating said grains with nitroglycerin in an amount less than 10% of the entire composition.

2. The method of preparing a granular explosive, which method comprises intimately intermingling a preponderant amount of ammonium nitrate, starch, a carbonaceous ingredient, and a salt containing water of crystallization, subjecting the blended mixture to a temperature sufficient to fuse said salt containing water of crystallization, forming the blend of materials into distinct agglomerates of controlled size, cooling to convert said agglomerates into firm, free-flowing grains, and coating the surface of said grains with nitroglycerin in an amount less than 10% of the entire composition.

3. A detonating explosive especially adapted to the mining of coal, comprising a blend of ammonium nitrate, a carbonaceous combustible material, and a binder substantially insoluble in nitroglycerin, said blend being in the form of firm sized aggregates of such size that substantially all are held on a 30-mesh screen, said aggregates having a surface coating of nitroglycerin in an amount not more than 10% of the entire explosive composition.

4. A detonating explosive especially adapted to the mining of coal, comprising a blend of ammonium nitrate, a carbonaceous combustible material, a binder substantially insoluble in nitroglycerin, and a salt containing water of crystallization, said blend being in the form of firm sized aggregates of such size that substantially all are held on a 30-mesh screen, said aggregates having a surface coating of nitroglycerin in an amount not more than 10% of the entire explosive composition.

5. A detonating explosive especially adapted to the mining of coal, comprising a blend of ammonium nitrate, a carbonaceous combustible ma-

glycerin, and a salt containing water of crystallization, said blend being formed of firm sized aggregates, and said aggregates having a surface coating of nitroglycerin in an amount not more than 10% of the entire explosive composition and sufficient to give a sensitivity of at least 10" as measured by the half cartridge sensitivity test.

6. A detonating explosive especially adapted to the mining of coal, comprising a blend of ammonium nitrate, a carbonaceous combustible material, a binder substantially insoluble in nitroglycerin, and magnesium nitrate hexahydrate, said blend being in the form of firm sized aggregates of such size that substantially all are held

15

on a 30-mesh screen, said aggregates having a surface coating of nitroglycerin in an amount not more than 10% of the entire explosive composition.

7. A detonating explosive especially adapted to the mining of coal, comprising a blend of ammonium nitrate, a carbonaceous combustible material and starch in hard tenacious form, said blend being in the form of firm sized aggregates of such size that substantially all are held on a 30-mesh screen, said aggregates having a surface coating of nitroglycerin in an amount not more than 10% of the entire explosive composition.

CHARLES D. BITTING.
